UNITED STATES PATENT OFFICE.

CHARLES G. PERKINS, OF NEW YORK, N. Y., ASSIGNOR TO THE IMPERIAL ELECTRIC LIGHT COMPANY, OF SAME PLACE.

INCANDESCENT LAMP.

SPECIFICATION forming part of Letters Patent No. 326,584, dated September 22, 1885.

Application filed September 7, 1883. (No model.)

To all whom it may concern:

Be it known that I, CHARLES G. PERKINS, a citizen of the United States, and a resident of New York, in the county of New York and State of New York, have invented certain new and useful Improvements in Electric Incandescent Lamps, of which the following is a specification.

My invention relates to improvements in multiple-filament incandescent lamps; and it consists, chiefly, in a novel arrangement of the filaments in the lamp, whereby during the incandescence of the filaments the light of all the series will be concentrated and appear like a solid glow. This property of my lamp adapts it especially for use in connection with parabolic reflectors, as on railway-engines and in lighthouses. I find it, however, to be a superior lamp for ordinary use, the apparent source of light being large and not affecting the retina, when looked at, with the keenly-unpleasant sensation which is produced when the source is the thin line of a single filament.

In the drawings which illustrate my invention, Figure 1 is an elevation of an incandescent lamp having four filaments arranged in accordance with my invention, and Fig. 2 is a plan of the filaments, the thickness thereof being exaggerated for the sake of clearness, and the lamp-globe being shown in section.

A is the globe of the lamp, within which the carbons *b c d e* are arranged in two pairs, as shown. The filaments *c e*, constituting one pair, are shown as parallel with each other and at right angles to the filaments *b d* of the other pair. This arrangement is not necessary, as the angle between the pairs may vary in the case of a larger number of filaments considerably from a right angle, and the filaments of each pair not be absolutely parallel, but only substantially so.

In case flat filaments are employed, the filaments of each pair are arranged to leave their flat faces parallel, and in arranging a larger number of filaments than four three or more 45 filaments would be similarly arranged in one or more of the groups.

The filament *b* is represented in the drawings as extending under *e* and over *c*. In like manner *c* extends over *d* and *d* over *e*. This 50 arrangement is likewise not essential, it being only necessary that the filaments should be grouped near each other, and so arranged that the plane of each filament will cut that of one of the opposite pairs at or near its inside. 55

Having now described my invention, what I claim, and desire to secure by Letters Patent, is—

1. The combination, in an electric incandescent lamp, of four looped filaments arranged 60 in two pairs, the filaments of each pair being in planes substantially parallel to each other, and substantially at right angles to the planes of the other pair, substantially as described.

2. The combination, in an electric incandescent lamp, of a group of flat looped filaments, every one of which is arranged to have its flat face substantially parallel with one or more of the others, and substantially at right angles to two or more of the others, whereby two or more 70 broad light-giving surfaces will be presented on every side of the lamp, and the carbons during incandescence will seem to give out light from a solid center, substantially as described. 75

Signed at New York, in the county of New York and State of New York, this 6th day of September, A. D. 1883.

CHARLES G. PERKINS.
